(57) **CLAIM**

The ornamental design for a miniature appliance leakage current interrupter, as shown and described.

DESCRIPTION

FIG. 1 is a front perspective view of the miniature appliance leakage current interrupter employing my new design; FIG. 2 is a rear perspective view of FIG. 1;

FIG. 3 is a top view of FIG. 1;

FIG. 4 is a bottom view of FIG. 1;

FIG. 5 is a left side view of FIG. 1;

FIG. 6 is a right side view of FIG. 1;

FIG. 7 is a top end view of FIG. 1; and,

FIG. 8 is a bottom end view of FIG. 1.

The broken line portion of the figure drawings is included to show unclaimed subject matter only and forms no part of the claimed design.
